FREDERICK E. MARTIN, OF BERKELEY, CALIFORNIA, ASSIGNOR TO MARTIN AIR DOG COMPANY, OF SAN FRANCISCO, CALIFORNIA, A CORPORATION OF CALIFORNIA.

TAPERING MECHANISM.

Continuation in part of application Serial No. 569,854, filed June 21, 1922. This application filed November 28, 1923. Serial No. 677,489.

To all whom it may concern:

Be it known that I, FREDERICK E. MARTIN, a citizen of the United States of America, residing at Berkeley, in the county of Alameda and State of California, have invented certain new and useful Improvements in Tapering Mechanism, of which the following is a specification.

This invention relates to improvements in tapering mechanism to be used in connection with saw mill operating mechanism, such as disclosed in my co-pending application for patent, filed November 25, 1921, Serial No. 517,647 the present application being a continuation in part of my application filed June 21, 1922, Serial No. 569,854.

In the prior application, Serial No. 517,647, I have shown fluid operated means to adjust the knees to taper a log, such means being under the control of the setter, so that within certain limits the knee may be adjusted to make a taper. However, the means shown in such application are substantially limited to but one taper adjustment, and this must be accomplished before the actual sawing of a log is commenced. In the present invention, there is provided means for affecting any one of a plurality of adjustments of the knee for tapering purposes, and also selecting and setting means, so that at the will of the setter, a selection can be made to determine the subsequent taper adjustment of the knee with absolute certainty, the means employed to determine a subsequent taper adjustment of the knee being so arranged and operative as to enable the setter to make a selection and set at any time, as for example, before or even during the actual sawing operation.

One of the principal objects of the present invention therefore is to provide means controlled by a setter to make a selection of any one of a plurality of permissible taper adjustments of the knee, the means serving to automatically lock the knee in certain of such adjusted positions, and at the same time prevent the possibility of any knee taper adjustment other than the predetermined one.

A further object of the invention is the provision of means, whereby before or during a sawing operation, a setter may make

a new selection for a subsequent and different taper adjustment, and if the selection is made during a sawing operation, upon completion of the saw cut and the return of the knee to normal position, such subsequent or new taper adjustment is automatically provided for, with all intermediate possible adjustments locked out, so that the next taper movement of the knee will have been positively predetermined by the previous selection.

To accomplish these results, it is essential that means be provided whereby an operator may, with convenience and at a time when he is not otherwise engaged in setting or selecting other devices in the system, operate selective means to position the parts to determine the extent of subsequent taper movement of the knee, and this without in any way affecting the position of the knee in its then adjusted or tapering position. The present invention contemplates means to secure this result, and to additionally provide an adjustment means, which while being under control of the selective means, is capable of direct operation to provide a subsequent limit taper adjustment when the knee is in withdrawn or normal position. The invention, stated more specifically, provides a series of stops on the knee, with any one of which a power operated knee taper lever may directly or indirectly cooperate to define a taper position of the knee, and to provide a taper lever limiting means independently controlled by selective mechanism, which may be operated to determine the stop which will limit the position of the taper lever and therefore determine the taper adjustment of the knee. The taper lever limiting means in addition to predetermining a limit position of the taper lever also serves to prevent cooperation of the taper lever and knee taper adjustment stop intermediate the normal position of the taper lever and the predetermined stop, thus not only selecting the subsequent limit position of the taper lever, but simultaneously eliminating all other possible limit positions of the taper lever.

The invention is illustrated in the accompanying drawings, in which:

Figure 1 is a view in elevation, showing

the improved taper adjusting means and the selective positioning means therefor, the adjusting means being in normal position and the positioning means at a neutral or normal set to determine the movement of the adjusting means for a tapering operation.

Figure 2 is a similar view, with the adjusting means operated to the position determined by the positioning means.

10 Figure 3 is a plan of Figure 1, the knee and knee-block being omitted.

Figure 4 is an enlarged broken elevation showing the positioning means operated in one direction beyond the normal or neutral position, the operating cylinder and control valve being each shown in section.

Figure 5 is a similar view, with the parts in the opposite position from neutral to that shown in Figure 4.

20 Figure 6 is a similar view with the parts in position determined by the neutral arrangement of the positioning means.

Figure 7 is a detail broken perspective view of the quadrant showing the arrangement of stops.

Figure 8 is an enlarged longitudinal section of the operating cylinder for the positioning means.

30 Figure 9 is an enlarged broken elevation of a modified form of the invention, showing the position as in Fig. 4.

Figure 10 is a similar view, the parts being in the same position shown in Fig. 5.

35 Figure 11 is a similar view, the parts being in the same position as shown in Fig. 6.

Figure 12 is a similar view showing a modified or two-step-positioning and adjustment means, with the particular operating cylinder and control valve therefor.

40 Fig. 13 is a diagrammatic view illustrating a modified arrangement of operating means.

In the invention, as illustrated, a conventional saw carriage, is indicated at 1, 2 indicates a knee block, and 3 indicates a knee, any usual connection, such for example, as indicated at 4, being employed between the knee and knee block to permit independent movement of the knee to taper a log, as heretofore contemplated and practiced.

45 A pin 6 carried by the knee pivotally supports a quadrant 7 having oppositely disposed extensions 8 and 9, the former being held in adjusted position with the knee by any of the well known spring means, as for example, as indicated at 10, while the latter carries a fluid pressure cylinder 11 hereinafter referred to as the taper cylinder. The connection 4 is provided with a lever 15, hereinafter termed the taper lever, and the upper end of this lever 15 passes through a slot in the end of a piston rod 16 connected to a piston 16^a in the taper cylinder, a cross pin 17 closing the forward end of the slot.

The taper lever passes through the quadrant 7, the latter being slotted at 15^a or compositely formed of plates to provide for the passage of the taper lever. The upper edges of the walls of the slotted portion of the quadrant are formed with notches or recesses in the form of teeth, which teeth provide one element of certain taper adjustment stops of the knee. Owing to the slotted formation of the quadrant, to provide for the passage of the taper lever there-through, and particularly where the quadrant in its forward portion is of reduced area, it has been found that the formation of a notch or tooth in the forward portion 70

80 of the quadrant tends to materially weaken the quadrant throughout this portion, and hence it has been found desirable to so form the slot 15^a that its forward end or wall

85 14^a may be utilized as one of the stops on the quadrant for the taper adjustment of the taper lever. Hence, in the preferred

form of the invention illustrated in Figs. 1 to 8, there are shown three taper adjustment 90

95 stops on the quadrant, two being in the form of notches or teeth, and the third the end wall of the slot 15^a. Of course, it will be understood that a greater or less number of notches or teeth may be provided in accordance with the number of taper adjustments

90 of the knee required, though ordinarily the provision of three such taper positions will be found sufficient. The taper lever 15 is provided with a pawl 19 pivotally connected to the lever at 18, the pawl being formed at

100 its free end for cooperation with the teeth or notches 12 and 13 and being additionally provided with a lateral stud 21, immediately in rear of its free end.

105 Obviously, in the forward movement of the taper lever under the power pressure means, the pawl 19 would engage the first or rear-most tooth 12, and the further movement of the taper lever and hence the taper of the knee would be arrested in a position determined by the limit movement of such lever. If a greater taper movement is required, the pawl may be placed in cooperation with the second tooth, as 13, and in the

110 limit movement of the taper lever, the knee is moved to a greater degree. If a maximum taper position of the knee is required, the pawl cooperation with the teeth 12 and 13 must be prevented and the taper lever moved independently of the knee until such

115 lever directly engages the end wall 14^a of the slot 15^a, whereupon the further movement of the taper lever and knee will be arrested. If, as is contemplated, these three,

120 or more if used, taper adjustments of the knee are to be selectively employed, that is, any one selected without regard to the then position of the knee, means must be provided whereby the pawl will be engaged

125 with the proper tooth, or prevented from

engaging any tooth during the operation of the taper lever, to cause said lever to engage the end wall 14^a of the slot 15^a. To secure this result, there is provided a locator or limiter for the control of the pawl, which locator or limiter, hereinafter termed the pilot lever, comprises an arm 22 pivotally supported on the pin 6 immediately adjacent one side of the quadrant 7. The upper end of the arm is provided with an extended head or guide section 23, which is disposed on a plane slightly above the toothed or notched edge of the quadrant, and is of a length slightly greater than the linear distance of that quadrant from the initial stop or tooth to the final stop. The forward end of the guide portion of the pilot lever is projected downwardly into U-form forming a recess 24, and then upwardly to present a terminal 25 above the normal plane of the guide. The extent of the recess 24 corresponds approximately to the depth of the teeth 12 and 13, and this head of the pilot lever guidingly receives the stud 21 of the pawl 19.

It will be of course apparent that while the stud is riding upon the concentric portion 23^a of the guide, the free end of the pawl is held out of possible engagement with any of the stop teeth, and that if the pilot lever has been arranged so that the recess 24 is substantially aligned with either of the stop teeth, it will be apparent that as the stud 21 rides into said recess, the free end of the pawl will drop into the corresponding tooth. Thus if the pilot lever has been adjusted to a position adjacent or in line with a particular tooth, the taper lever in its forward movement will cause the pawl to drop into that tooth, thereby locking the taper lever and knee to cause the knee to move with the further movement of the taper lever, and thus secure the desired extent of taper adjustment of the knee. If, however, it is desired that the taper lever engage the end wall 14^a of the slot 15^a, the movement of the pilot lever is such as to prevent the pawl from cooperation with any of the teeth, so that the pawl rides free of the teeth and forwardly until the taper lever engages the end wall of the slot. As previously stated, the guide portion 23^a of the pilot lever is of such length as to block out the limit stops other than the one selected, so that if this pilot lever has been moved to a position to permit the taper lever to engage the end wall of the slot, the guide portion 23^a will overlie all other stops in the quadrant, so that the pawl will ride freely over the same in the movement of the taper lever to the limit position. In cooperation with any particular stop tooth, the pilot lever permits the pawl to engage that tooth through allowing the stud 21 of the pawl to ride into the recess 24 of the pilot lever. In the extreme forward stop position of the taper lever, however, that is, with such lever in engagement with the end wall 14^a of the slot, the pilot lever has been moved to a position to prevent the pawl 70 from engaging with any of the teeth, and as the taper lever approaches the stop 14^a, the pawl simply rides on the upper edges of the side walls of the quadrant, as clearly shown in Fig. 5, wholly free of and beyond the influence of the pilot lever.

Thus the pilot lever absolutely predetermines a particular stop position of the taper lever with respect to the knee, the pilot lever guiding the pawl into the particular tooth, where such tooth forms the selected stop, or preventing the pawl from engagement with any of the teeth, where the taper lever is to be moved into cooperation with the wall 14^a as a stop.

The pilot lever is controlled by means of a fluid cylinder 27 pivotally supported at 26 on the quadrant and having a piston 28, and a piston rod 29, the latter of which is connected to the pilot lever. The cylinder 27, hereinafter termed the pilot cylinder, comprises a central barrel 30 with end heads 31. In the rear head is a loose fitting disc 32, and between the same and the rear wall of the head is interposed a spring 33, the tension of which tends to normally hold the disc up against the end of the barrel and against or adjacent an extension 34 of the piston. In the front head is a loose fitting disc 35, and between such disc and the end wall of the front head, is interposed a spring 36, the tension of the same tending to normally hold the disc up against the end of the barrel and up or against a flange 37 formed on the rod 29. In the heads are ports 38 and 39 connected by pipes 40 and 41 to ports 42, 43, of the cylinder 44 of a controlling valve 45. The valve 45 is reciprocally mounted in the cylinder, and is conveniently connected to a handle 46, positioned to be operated by the setter in connection with the unit control described in the co-pending application, Serial No. 517,647 hereinabove referred to.

In operation of the form shown more particularly in Figs. 1 to 8, and assuming the parts to be in normal positions, that is, with the taper lever, and therefore the knee, fully withdrawn, which is the position of the knee, when no taper is required, the piston 28 of the pilot cylinder is held in balanced positions by the springs 33, 36, and the pilot lever is arranged so that the U-shaped depression 24 is substantially in line with the tooth or notch 13. With the parts in this normal position, and pressure admitted to the taper cylinder to advance the taper lever, the pawl 19 by reason of the pin 21 riding on the guide section 23^a of the taper lever will ride over the initial notch or tooth 12 130

and enter the notch 13 as shown in Fig. 6. This movement of the taper lever 15 causes a corresponding movement of the knee and thus a taper adjustment of the knee to an extent determined by the movement of the taper lever before being interlocked with the knee by the pawl engagement described. The pressure in the taper cylinder is maintained during the tapering operation, and as the stud 21 of the pawl is in the lower portion of the recess 24 of the pilot lever, and as the nose of the pawl is in engagement with the tooth, it will be apparent that the parts are substantially locked in this position as the stud 21 cannot move upwardly in the recess owing to the rearward curve of the forward wall thereof, as shown, and the pressure of the taper cylinder prevents any rearward movement of the pawl. This effective interlock is maintained as long as pressure remains in the taper cylinder, and is not broken until this pressure is relieved and opposing pressure applied to move the taper lever back to a normal position.

It will be apparent from the above description that when the pilot lever is interlocked with the teeth 12 or 13, as when the taper lever is in tapering position determined by such teeth, the pilot lever cannot be directly moved, but as hereinafter described, is under these circumstances, adapted to be set or influenced for its next move at the will of the operator, and the pilot lever will respond to this previous set or influence when the taper lever has been returned to normal position and the interlock released. If, however, the taper lever is in normal position, or is in engagement in taper position with the stop 14^a, it will be seen that the pilot lever is wholly free of any interlock, and if under these circumstances a decreased taper movement of the knee is desired, the taper lever is moved to normal position by appropriate pressure in the taper cylinder and the setter moves valve 45 to a position indicated in Fig. 4, to admit pressure through pipe 41, and thus, through the pressure on piston 28, move the pilot lever rearwardly until the recess 24 is in alignment with the tooth 12. If preferred, the result just noted may be as readily accomplished by initially operating the pilot lever which may be first adjusted to the desired position, and the taper lever then operated, as with the taper position determined by stop 14^a, the pilot lever is free to be adjusted at will. In this position, the arm 22 of the pilot lever engages with what may be called an adjustable rear stop for such pilot lever, indicated at 48. As the taper lever moves forwardly under appropriate pressure, the nose of the pawl 19 will be guided into the tooth 12 through the stud 21 riding in the recess 24 and the movement

of the taper lever will be arrested, and thereby the taper movement of the knee will be stopped.

If an increased taper is desired, the setter shifts valve 45 to the position indicated in Fig. 5, admitting pressure through pipe 40 and operating the pilot lever through appropriate pressure on the piston 28 in the pilot cylinder forwardly until limited by the forward pilot lever stop 49, which is in the form of an adjustable screw. In this position the forward or notched end of the guide of the pilot lever is in advance of the wall stop 14^a of the slot 15^a, and as the quadrant is not cutaway or notched at this point, the upper edge of the walls on opposite sides of and beyond the slot are upwardly curved as at 50 to maintain the outline of the part. In the forward position, the pilot lever is arranged so that the main guide portion 23^a lies in a plane above the notches or teeth 12 and 13, and the terminal 25 of the forward wall forming the depression 24, which as it will be seen, terminates in the curved plane of the main length of the guide is now but slightly above the curved portion 50 of the quadrant. As pressure is admitted to the taper cylinder, the taper lever moves forwardly, the stud 21 of the pawl 19 riding on the guide portion 23^a of the taper lever to prevent the pawl from entering either of the teeth 12 or 13. As the taper lever reaches a position approximating the predetermined stop, which in this instance is the forward wall 14^a of the notch 15^a, the nose of the pawl rides upon the curved portion 50 of the quadrant, and the relation of the parts is such, as shown more particularly in Fig. 5, that as the taper lever continues to move forwardly, the pawl is elevated by this curved portion 50 of the quadrant, so that the stud 21 of the pawl 19 rides over the free end 25 of the forward wall of the depression 24 of the taper lever guide. The taper lever will engage the stop 14^a and thus limit the taper movement of the knee, but this movement is the maximum movement as the control or limiting mechanism is so positioned as to permit the maximum movement of the taper lever.

In Figs. 9 to 11 inclusive, there is illustrated a slightly modified form of the taper limiting means, hereinbefore described, wherein instead of limiting the maximum movement of the taper lever by the forward wall 14^a of the notch 15^a, the quadrant is provided with a forward tooth 14 as a co-operating stop element. This modified construction is designed for use in those saw mill rigs where the quadrant can be constructed of such size and strength as to avoid liability of breakage in use through the formation of this third or forward notch or tooth. The parts previously described in connection with the taper mecha-

nism are duplicated in this modified construction, except that in the movement of the taper lever to the maximum disposition, the stop 49 limits the forward movement of 5 the taper lever, so that the depression 24 thereof is in alignment with such forward notch or tooth 14, and as the taper lever moves forwardly under the second pressure in the taper cylinder, the stud 21 is guided 10 into the depression 24 of the taper lever and the free end of the pawl is thereby guided into the notch or tooth 14.

In the modified form, it will be noted that 15 in Fig. 11, the pilot lever 22 is shown as in the normal position, that is, with the notch 24 in cooperation with the tooth 13, and the taper lever 15 has been advanced to the corresponding taper position, wherein the pawl 19 will be directed by the guide portion of 20 the taper lever and the recess 24 into cooperation with the tooth 13. If in this modified form, a less taper is desired, the movement of the taper lever back to normal position will release the pilot lever, and either 25 before or after said release, the setter will manipulate the valve 45 to admit pressure to the pipe 41 and so operate the piston 28 as to move the taper lever back into cooperation with the tooth 12, whereupon the 30 movement of the taper lever under pressure will cause the pawl to engage this tooth 12, as indicated in Fig. 9, thus moving the knee to the minimum taper position. If an increased taper is desired, the taper lever will 35 be returned to normal position and the valve 45 operated to move the pilot lever, so that the notch 24 registers with the tooth 14, whereupon on operating the taper lever, the same will be moved, together with the knee, 40 until the pin 21 of the pawl 19 engages in the recess 24 of the pilot lever, causing the pawl to enter tooth 14, as shown in Fig. 10. This is the maximum taper position of the modified form, and in each instance the position of the pilot lever accurately and absolutely determines the taper.

In this modified form, it will be apparent 45 that in each taper adjustment, the pilot lever and pawl will be locked relative to each other and to the particularly engaged notch, or tooth, until the pressure on the taper lever has been relieved and said lever has been moved rearwardly toward the normal position; while in the preferred form, this interlock between the pawl of the taper lever and the pilot lever is in effect only for the two teeth or notches 12 and 13, the forward or maximum position of the taper lever not utilizing the pawl as a limiting means and 50 holding said pawl free of the pilot lever, so that the latter following the maximum disposition of the taper lever may, by appropriate and obvious control of the valve 45, be set to a subsequent position. In this 55 setting to a subsequent position of the pilot

lever while the taper lever is at its maximum taper position, as for example, the setting of the taper lever for cooperation with the tooth or notch 12, the taper lever 70 pawl 19, in the return of the taper lever to normal position, rides over the forward wall of the depression 24, the stud 21 riding up the outer side of said wall and reaching the main guide portion 23^a, where any previously indicated operation for taper control may 75 be carried out.

An essential and important feature of both forms of the invention herein set forth is that the pilot lever is capable of being set or adjusted to predetermine a subsequent 80 position of the taper lever without regard to the position of the taper lever when such selection or set of the pilot lever is made. Under those conditions in both the preferred and modified forms, where the taper lever and pilot lever are locked relative to each other while the taper lever is under pressure, for example, in the preferred form, when the pawl 19 is engaged with either 85 the teeth 12 or 13, and in the modified form 90 where the taper lever pawl is in engagement with either of the teeth 12, 13 or 14, it is apparent that the setter may, while the parts remain in this interlocked condition, manipulate the valve 45 and admit pressure 95 to the pilot cylinder 30 which, if the pilot lever were free to move, would set such pilot lever in proper relation to the next predetermined position of the taper lever. However, with the pilot lever in interlocked position, it is held against this movement following the set thereof described, by the fact 100 that the pressure in the taper cylinder is greater than the pressure in the pilot cylinder, and the further fact that the nose of the 105 pawl abuts against the face of the tooth and holds the taper lever against displacement in a forward direction while the stud 21 engaged in the depression 24, holds the pilot lever against movement in the rearward direction. As soon however, as the pressure in the taper cylinder is relieved, and the 110 taper lever started toward normal position, the interlock described is broken and the pressure in the taper cylinder as previously set, exerts itself and moves the pilot lever to the new position. Upon the next forward movement of the taper lever, the new position of the pilot lever determines 115 the taper limit movement of the taper lever.

This interlocked relation of the pilot lever and the setting of the pilot lever at will for subsequent movement to the new taper position when the interlock is broken is 120 equally true of the preferred form when either of the teeth or notches 12 or 13 are used as the taper limit.

In the preferred form when the taper lever is in maximum taper position, that is, 125 in engagement with the wall 14^a of the re-

cess 15^a, the pilot lever, as indicated in Fig. 5, is wholly free of connection with the pawl, and such pilot lever may be then freely set to any desired position to determine a subsequent limit movement of the taper lever. It is of course equally true that when the taper lever is in normal or fully retracted position, the pilot lever is free and may be adjusted to any one of the several limit positions desired to control the subsequent movement of the taper lever.

Therefore, it may be stated that the pilot lever provides a means for determining a knee taper movement of a taper lever and that this pilot lever may be so controlled when the pilot lever is in any of its taper adjusting positions that the subsequent or succeeding adjusting position of the taper lever may be provided for, whereby while the knee is in a taper position and so held by the taper lever, the setter may determine the next taper position and arrange the parts so that the next taper movement of the taper lever will be predetermined. It is through this ability to set the pilot lever, if interlocked, or to actually adjust it if free to move, to a position which will determine the next taper position of the taper lever, without regard to the fact that the taper lever is set and holding the knee in a particular taper position or not, that the importance of the taper mechanism depends, for by this arrangement, the setter may determine a subsequent taper while the log is being cut, and while he is not otherwise engaged in setting and selecting other devices in the system.

Obviously, the invention is not limited to a construction which will permit of three adjustments for tapering. For instance, in Fig. 12, the cylinder 27^a which operates the arm 22, is provided with a piston 28, and its rod 29 is pivoted to the arm and operates the same as in the preferred form. However, the fluid pressure from the valve 44^a acts to only force the piston and arm in one direction. A spring 36^a is interposed between the piston and one end of the cylinder to return the arm to normal position. This arrangement is illustrative of a type of construction, wherein but two taper adjustments are required, consequently, the quadrant 7 will have but two teeth 12^a and 13^a. In other respects, that is, the flanged head and recess and the pressure means for operating the knee are the same as in the preferred form.

In the modified form of the invention, the valve 44^a is moved to admit pressure in the chamber 59 of the cylinder, and the arm 22 is rocked forwardly until it encounters the limiting stop, at which time the recess 24 is located to receive the stud on the pawl and cause the latter to engage the tooth 14^a. When the valve 44^a is reversed, pressure is

exhausted from the chamber and the spring 36^a returns the piston and the arm to normal position against the limiting stop at which time the recess 24 is located to cause the pawl to engage tooth 13^a when the knee is subsequently advanced.

While the invention described is primarily intended to operate in conjunction with and form a part of the unit control system for operating saw mill carriages, as fully shown and described in the application herein referred to, it is nevertheless not limited in its use to this particular combination. There are many and varied conditions where tapering mechanism such as described may be used to advantage without employing all the elements of the whole unit control system. However, in every instance, it is essential toward accuracy and increased economical production, that the tapering means be so designed and arranged that the setter may select and set the adjustment for an immediate or future taper control at a time when his attention is not otherwise required in connection with other things on the carriage. With this end in view, it is evident the construction and operation set forth will accomplish the contemplated result, and in addition the setter has little to do to make the required adjustment.

In the description and drawings, the invention has been shown and described in connection with a single knee, but is of course to be understood that all knees and knee blocks on a carriage are or may be similarly constructed.

The various operations herein described are shown as fluid operated, and while this is a particularly convenient means for carrying out the desired functions, it is to be understood that the parts may well and with equal facility be operated by any power means. For example, a simple and convenient electrically-operated control may be provided, wherein the taper lever here indicated at 60 may be provided with a curved rack bar 61, adapted to be engaged and operated by a pinion 62 driven directly or indirectly by a reversible motor 63 controlled by a switch 64. The pilot lever 65 may have an operating rod 66 provided with an armature 67 cooperating selectively with either of two (or more) electromagnets 68, the selective energization of a particular electromagnet attracting the armature and correspondingly moving the pilot lever. Springs 69 may be employed in connection with the electromagnets, which springs are so mounted with relation to and so control the operating rod of the pilot lever (or such pilot lever directly) as to tend to move the pilot lever to a normal or central position when the electromagnets are de-energized.

Thus through appropriate switch manipu-

lation, the entire mechanism may be conveniently and efficiently controlled electrically. Therefore, in the appended claims the reference to power or fluid operated is intended to cover any and all mechanical and electrical equivalents for the operation, control, and setting of the parts.

What I claim is:—

1. In combination, a knee and knee block connected for independent movement of the knee, means for adjusting the knee independent of the knee block, means to limit the adjustable movement of the knee, including teeth and a pawl to cooperate with the teeth, and means selectively operable at the will of the operator to subsequently establish which tooth the pawl will engage for limiting the adjustable movement of the knee.
2. Log tapering means for a saw mill carriage, comprising a knee block, a knee having movement independent of the knee block, means for adjusting the knee independent of the knee block to taper a log, means for predetermining and limiting such movement, and means permitting a setting of the limiting means for a subsequent adjustment of the knee toward a log when the knee is in either retracted or tapering position.
3. Log tapering means for a saw mill carriage, comprising a knee block, a knee having movement independent of the knee block, means for adjusting the knee independent of the knee block to taper a log, means for predetermining and limiting such movement, including teeth and a pawl, and means operable when the knee is in either retracted or tapering position to select which one of the teeth the pawl will engage to determine the length of the next tapering movement of the knee.
4. Log tapering means for a saw mill carriage, comprising a knee block, a knee having movement independent of the knee block, means for adjusting the knee independent of the knee block to taper a log, means for predetermining and limiting such movement, and selecting means capable of being set for determining which tooth the pawl will engage to determine the depth of the tapering movement when the knee is in retracted or tapering position, or while a log is being sawed.
5. In combination, a saw mill carriage, a knee on the carriage to set a log, means capable of predetermining the adjustment of the knee to vary the depth of the taper of a log, and setting mechanism operable while the carriage is in movement or at rest and irrespective of the position of the knee to predetermine the extent of the subsequent adjustment of the knee.
6. Means for tapering a log on a saw mill carriage, including setting mechanism oper-
- able for determining the extent of a subsequent taper during the time the knee is adjusted against a log, whereby to provide for subsequent taper of the log without effecting such position or the sawing operation.
7. In combination, a knee and knee block for a saw mill carriage, means for imparting adjustable movement of the knee independently of the knee block, a pawl carried by said means, a series of teeth on the knee with which the pawl cooperates, a selective mechanism including a lever and device to cause the pawl to engage a predetermined tooth of the series to limit the adjustable movement of the knee, and setting means operable at all times to determine a selective movement of the lever and device.
8. In combination, a knee and knee block for a saw mill carriage, means for imparting adjustable movement of the knee independently of the knee block, a pawl carried by said means, a series of teeth on the knee with which the pawl cooperates, a selective mechanism including a lever and a device to cause the pawl to engage a predetermined tooth of the series to limit the adjustable movement of the knee, and setting means to determine a subsequent selective movement of such lever and device independent of the then position of such parts with reference to the pawl, and springs to return said lever and device to normal position at the will of the operator.
9. Means for tapering a log on a saw mill carriage, comprising a knee and knee block, means for imparting adjustable movement to the knee independent of the knee block, means for predetermining the extent of such adjustable movement, and fluid pressure setting means operated to determine a subsequent set of the means for determining the extent of the movement of the knee, said fluid pressure means being operable irrespective of the position of said knee, and springs to return such knee determining means to normal position at the will of the operator.
10. Means for tapering a log on a saw mill carriage, comprising a knee and knee block, means for imparting adjustable movement to the knee independent of the knee block, a pawl carried by the last mentioned means, a stud on the pawl, teeth carried by the knee, an arm mounted on the knee and provided with a flanged head and cam recess with which the stud cooperates to determine which tooth the pawl will engage to limit the extent of movement of the knee in a tapering operation, a cylinder, a piston in the cylinder having a rod extending therefrom and pivoted to the arm, springs for holding the arm in a normal position with reference to the teeth, and means for controlling fluid pressure to actuate the arm to position the recess and cause the stud to engage a selected tooth and limit the movement of the knee.

11. Means for tapering a log on a saw mill carriage, comprising a knee and knee block, means for imparting movement to the knee independent of the knee block, means for selecting and determining the extent of the independent movement of the knee and effecting an interlock between such means and the knee during a tapering operation, and means controlled by a valve for making a subsequent selection of the extent of movement of the knee when the knee is in normal or interlocked position.
12. In combination, a knee and knee block for a saw mill carriage, means for imparting movement to the knee independent of the knee block, including fluid pressure means, a pawl carried thereby, teeth on the knee with which the pawl engages, means for operating the knee and knee block together, and means controlled by a valve for predetermining which of the teeth the pawl will engage and when engaged form an interlock between the knee and the fluid pressure means, the interlocking action and valve permitting of making a selection from the teeth for changing the extent of movement of the knee for a subsequent tapering operation while the knee is locked and engaging a log.
13. In combination, a knee and knee block for a saw mill carriage, means for holding the knee and knee block in normal position and operating same in unison, means for imparting movement to the knee independent of the knee block including a fluid pressure cylinder, piston, piston rod and lever, a pawl carried by the lever, teeth carried by the knee, and means cooperating with the pawl to cause engagement of same with one of the teeth to predetermine the extent of the independent movement of the knee during the time a log is being cut on a taper or when being cut straight without affecting the position of the knee while making the cut, and a valve for operating the pawl cooperating means.
14. In combination, a knee and knee block for saw mill carriage, means for imparting movement to the knee independent of the knee block, a pawl carried by such means, teeth carried by the knee, an arm having a device to cooperate with the pawl to cause same to engage a predetermined tooth, stops to limit the movement of the arm, springs to hold the arm in a normal position with reference to the teeth, and fluid pressure operated means to actuate the arm to position the device carried thereby to cause the pawl to engage a selected tooth and thereby determine the extent of the independent movement of the knee.
15. In combination, a knee and knee block for saw mill carriages, pressure operated means for moving the knee independent of the knee block, a pawl carried thereby, a stud on the pawl, teeth carried by the knee,
- an arm mounted on the knee, said arm having a track and a cam recess, pressure operated means for actuating the arm to position the cam recess to receive the stud and cause the pawl to engage the selected tooth and thereby limit the extent of movement of the knee and form an interlock between the arm and pawl, and a valve for controlling the pressure operating means for actuating the arm, the interlock and the pressure necessary to operate the arm being less than the pressure necessary to independently move the knee permitting of actuation of the valve for making a subsequent selection of a tooth with which the pawl is to engage while the knee is set in a tapering position.
16. In combination, a knee and knee block for saw mill carriages, pressure operated means for imparting to the knee a movement independent of the knee block, a pawl and cooperating teeth between the knee and pressure operated means for limiting the adjustment of the knee, and selecting mechanism fully operable in any relation of the parts to predetermine which tooth the pawl will engage in a subsequent operation to limit the extent of movement of the knee under the pressure operated means.
17. In combination, a knee and knee block for saw mill carriages, pressure operated means for imparting to the knee a movement independent of the knee block, a pawl and cooperating teeth between the knee and the pressure operated means, selecting mechanism to predetermine which tooth the pawl will engage to limit the extent of movement of the knee in a tapering operation, including a device to cause an interlock between the pressure operated means and the pawl when the latter engages a tooth, and means operable while the pressure operated means and pawl are interlocked to make a predetermined selection of extent of movement of the knee in a subsequent tapering operation.
18. A log taper adjusting means for saw mill carriages, and automatically operable control means for said adjusting means, said control means being set at will for subsequent automatic operation and released for such operation only under predetermined conditions of the adjusting means.
19. A log taper adjusting means for saw mill carriages, and automatically operable control means for said adjusting means, said control means being set at will for automatic operation and held against the automatic operation for which it is set while the adjusting means is in operative position, whereby to permit setting the control means while the adjusting means is holding the parts of the carriage in one log adjusting position.
20. In a log tapering mechanism, a log taper adjusting means, and an automati-

ically operable mechanically set limit member for said adjusting means, the operative movement of which is controlled by the adjusting means.

5 21. In a log tapering mechanism, a log taper adjusting means, and limit mechanism therefor, said mechanism being set for an automatic operation to determine a subsequent position of the adjusting means and held against such automatic movement by the adjusting means when in operative position.

10 22. In a log tapering mechanism, a log taper adjusting means and a locator therefor, manually controllable automatic means for operating and positioning said locator, said means being held against locator operation by said adjusting means when in operative position, whereby on release of said 15 adjusting means the locator is released for operation under the previously set automatic means.

20 23. A log taper adjusting means, and means for determining a subsequent position of such adjusting means, said determining means being set for automatic movement following release of the adjusting means.

25 24. In a log tapering mechanism for saw mill carriages, an adjusting means for controlling the log taper, means for differentially limiting the operation of said adjusting means in any one operative movement, means for establishing a potentiality 30 for variation in said limit through a previously manually governed setting, the operation of said potentiality being directly controlled by the adjusting means.

35 25. In a log tapering mechanism for saw mill carriages, a log taper adjusting means, a limit position member therefor, means for setting the member for automatic movement, said adjusting means controlling the direct movement of said member.

40 26. A locator for saw mill carriage knee adjusting means, said locator being held against independent movement by the adjusting means when in operative position, an automatic positioning means for said locator capable of being set while said adjusting means is in operative position and operating on the locator following its release by movement of the adjusting means from operative position.

45 27. A log taper setting means for saw mill carriages, and control means for limiting the movement of such setting means, said control means being adjustable for predetermined operation without regard to the 50 position of the setting means and released for such predetermined operation under certain conditions of such setting means.

60 28. A log taper adjusting means for saw mill carriages, and locating means adapted to be manually set for determining a sub-

sequent position of such adjusting means, said locating means being held against movement responsive to such manual set by and while the adjusting means is in an operative position.

70 29. A log taper adjusting means, and means for variably limiting the operative movement of such adjusting means, an actuator for the limiting means adapted to be set at will for changing the position of 75 the limiting means, said adjusting means while in an operative position holding the limiting means against movement responsive to the set of the actuator.

80 30. A saw mill carriage knee adjusting member, a plurality of elements on the knee with which said member may engage to limit the adjustment of the knee, and means for selectively determining with which of said elements the member will subsequently 85 cooperate, said means being capable of being set while said member is in operative engagement with one of said elements for later automatic operation.

90 31. A saw mill carriage knee adjusting member, a plurality of elements on the knee with which said member may engage to limit the adjustment of the knee, and means for selectively determining with which of said elements the member will subsequently 95 cooperate, said means being capable of being set while said member is in operative engagement with one of said elements.

100 32. A saw mill carriage knee adjusting member, a plurality of elements on the knee with which said member may engage to limit the adjustment of the knee, and means for selectively determining with which of said elements the member will subsequently 105 cooperate, said selective means being automatically and simultaneously responsive to the selection when the member is in normal position or subsequently responsive to the selection if the member is in cooperation with one of said elements at the time of 110 selection.

115 33. A saw mill carriage knee adjusting member, a plurality of elements on the knee with which said member may engage to adjust the knee, a locator to be positioned with respect to a predetermined one of said elements and thereby compel the cooperation of said member and that element, and means whereby the locator may be set for positioning with respect to any one of said 120 elements, said locator being simultaneously responsive to the setting means if said member is free of cooperation with any of said elements and subsequently responsive to the setting means if the member is in cooperation with any of said elements at the time of setting.

125 34. A saw mill carriage knee adjusting member, an element movably mounted on the knee to form a guide for and limit the 130

position of said member in the knee adjusting movement, and means whereby the element may be set at any time for movement to a new position.

5 35. A saw mill carriage knee adjusting member, an element movably mounted on the knee to form a guide for and limit the position of said member in the knee adjusting movement, and means whereby 10 the element may be set at any time for movement to a new position, the cooperation of said member and element serving to lock said element against movement responsive to such set while said lock is maintained.

36. In a log tapering mechanism, a log tapering means, and a limit member to determine the extent of movement of said tapering means, and means operative in any 20 position of the parts to predetermine a subsequent position of said limit member.

37. In a log tapering mechanism, a taper adjusting means, means to define the limit movement of such adjusting means, means 25 for operating said defining means to different positions, said operating means being capable of being set for subsequent actuation while the adjusting means and defining means are in operative relation.

38. A log taper adjusting means for saw mill carriages, and control means to define the limit position of such adjusting means, said control means being capable of automatic response to any predetermined set 35 perfected during an active cooperation of said adjusting means and control means.

39. A log taper adjusting means having a plurality of different limit positions, and means to predetermine a subsequent limit 40 position during any particular limit position, said predetermining means perfecting the new limit position following movement of the adjusting means from the particular limit position.

40. A log taper adjusting means having a plurality of different limit positions, and means to predetermine a subsequent limit position during any particular limit position, means for restraining the effective operation of said predetermined means but releasable to leave the latter free to act, said predetermining means automatically defining the new limit position when free to act.

41. In combination, a knee and knee block 55 connected for independent movement of the knee, means for adjustably positioning the knee independent of the knee block, including a series of teeth, a lever, and pawl, means to cause the pawl to engage a predetermined tooth, and setting means operable at will to determine a subsequent movement of the lever independent of the then position of the pawl.

42. In combination, a knee and knee block 60 connected to permit independent movement

of said knee, means to cause such independent knee movement, means for limiting such knee movement to any one of a series of determinate positions, including stops and a cooperative element, and setting means 70 operative at will to predetermine a subsequent limiting relation between said cooperative element and one of said stops, said setting means serving to hold the cooperative element against cooperation with any 75 of the stops other than the predetermined one.

43. In combination, a knee and knee block connected to permit independent movement of said knee, means to cause such independent knee movement, means for limiting such knee movement to any one of a series of determinate positions, including teeth, and a pawl to cooperate with the teeth, and setting means operative at will to predetermine a 80 subsequent limiting relation between said pawl and one of the teeth, said setting means holding and guiding the pawl free of all teeth other than the predetermined one.

44. Log tapering means for a saw mill 90 carriage, comprising a knee, a member operative to move the knee for tapering a log, means to limit the movement of the member to any one of a plurality of positions to thereby vary the taper position of the knee, and a selective means to determine at will the particular limit means to be next employed, said selective means preventing the control of the member by any other limit means than that selected.

45. Log tapering means for a saw mill carriage, comprising a knee, a member operative to move the knee for tapering, successive stops to limit the movement of the member to any one of a plurality of positions to thereby vary the taper position of the knee, and a selective means to determine at will the particular stop to be next employed to limit the member, said selective means serving to prevent the use of any stops as a limit for the member other than that selected.

46. Means for tapering a log on a saw mill carriage, including setting mechanism 115 operable for determining the extent of a subsequent taper during the time the knee is adjusted against a log, the setting means simultaneously eliminating any other subsequent taper than that determined.

47. In combination, a knee mounted for 120 taper movement, a member to cause such tapering movement, means for limiting the member to any one of a series of determinate positions, including a series of successive stops, and setting means operative at will to predetermine a subsequent cooperation between the member and any one of the stops, said setting means at the same time preventing the cooperation of the member 125 and any other of the stops.

48. In combination, a knee, a member for moving the knee for tapering a log, a series of stops to limit the tapering movement of the member, a pawl on the member to cooperate with certain of said stops, said member directly cooperating with another of said stops independently of the pawl, and setting means whereby the movement of the pawl is controlled to select any one of such stops as a limiting means.

49. In combination, a knee, a member for moving the knee for tapering a log, a series of stops to limit the movement of the member, a pawl on the member to cooperate with certain of said stops, said member directly cooperating with another of said stops independently of the pawl, and independent means whereby the particular stop for limiting the movement of the member may be selectively predetermined.

50. In combination, a knee, a member for moving the knee for tapering a log, a series of stops to limit the movement of the member, a pawl on the member to cooperate with certain of said stops, said member directly cooperating with another of said stops independently of the pawl, and independent means whereby the particular stop for limiting the movement of the member may be selectively predetermined, said means serving to prevent member cooperation with any of the stops other than the one selected.

51. In combination, a knee, a member for moving the knee for tapering a log, a series of stops to limit the movement of the member, said stops including a plurality of notches, and an abutment, a pawl on the member to cooperate with the notches, said member directly cooperating with the abutment, and setting means whereby the notches or abutment may be selected as the limit stop for the member in a tapering operation.

52. In combination, a knee, a taper lever for moving the knee, a plurality of teeth to serve as stops for said taper lever, a knee abutment to serve as a stop for the taper lever, a pawl on the lever to cooperate with the teeth, said lever directly cooperating with the abutment independently of the pawl, and an independently controlled pilot lever adapted to cooperate with and guide the pawl into a particular tooth or hold the pawl from cooperation with any of the teeth to permit the lever to engage with the abutment.

53. In combination, a knee, a taper lever for moving the knee, a plurality of teeth to serve as stops for said taper lever, a knee abutment to serve as a stop for the taper lever, a pawl on the lever to cooperate with the teeth, said lever directly cooperating with the abutment independently of the pawl, and an independently controlled pilot lever adapted to cooperate with and guide the pawl into a particular tooth or hold the pawl from cooperation with any of the teeth to permit the lever to engage with the abutment, and means for selectively operating the pilot lever.

54. In combination, a knee, a taper lever for moving the knee, a plurality of teeth to serve as stops for said taper lever, a knee abutment to serve as a stop for the taper lever, a pawl on the lever to cooperate with the teeth, said lever directly cooperating with the abutment independently of the pawl, and an independently controlled pilot lever adapted to cooperate with and guide the pawl into a particular tooth or hold the pawl from cooperation with any of the teeth to permit the lever to engage with the abutment, said pilot lever being interlocked with the pawl when the latter is in engagement with one of the teeth and being wholly free when the taper lever is in engagement with the abutment.

55. In combination, a knee, a taper lever for moving the knee, a plurality of teeth to serve as stops for said taper lever, a knee abutment to serve as a stop for the taper lever, a pawl on the lever to cooperate with the teeth, said lever directly cooperating with the abutment independently of the pawl, and an independently controlled pilot lever adapted to cooperate with and guide the pawl into a particular tooth or hold the pawl from cooperation with any of the teeth to permit the lever to engage with the abutment, said pilot lever being interlocked with the pawl when the latter is in engagement with one of the teeth and being wholly free when the taper lever is in engagement with the abutment, said pilot lever capable of actuation at will and serving to subsequently influence said pilot lever following the release of the interlock or to immediately influence the pilot lever if the latter is free.

In testimony whereof I affix my signature.

FREDERICK E. MARTIN.
